(57) **CLAIM**

The ornamental design for a watch bezel, as shown and described.

DESCRIPTION

FIG. 1 is a perspective view of a watch bezel with a hinged element shown in a first use position.

FIG. 2 is a perspective view of the watch bezel shown with the hinged element at a first transition point between the first use position of FIG. 1 and a second use position.

FIG. 3 is a side view showing the watch bezel with the hinged element in the first use position;

FIG. 4 is a side view of the watch bezel with the hinged element shown at the transition point shown in FIG. 2;

FIG. 5 is a side view of the watch bezel with the hinged element in a second transition point between the first and second use positions.

FIG. 6 is a side view of the watch bezel with the hinged element in a third transition point between the first and second use positions.

FIG. 7 is a side view of the watch bezel shown with the hinged element in the second use position.

FIG. 8 is a top view of the watch bezel with the hinged element shown in the first use position; and,

FIG. 9 is a top view of the watch bezel shown with the hinged element in the second use position with the entire bezel shown rotated approximately 45 degrees counter-clockwise.

The structures depicted by means of broken lines in the figures have been shown for illustrative purposes only and form no part of the claimed design.
